UNITED STATES PATENT OFFICE.

WILLIAM A. GEIGER, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed February 5, 1926. Serial No. 86,170.

This invention relates to anti-friction bearings.

An object of the invention is to provide a simple, practical, relatively inexpensive bearing, especially adapted for railway car side bearings, in which the parts are so arranged that the anti-friction elements are automatically returned to the normal centered position when free from load.

Another object of the invention is to provide a side bearing of this character including a retainer adapted to be disposed upon the truck bolster of a railway car and having anti-friction means disposed therein and adapted to move to and fro with reference to said mounting, in conjunction with transmitting elements slidably associated with the mounting and arranged to bear upon the outer sides of the anti-friction means above the central axis thereof, together with resilient means connecting said transmitting members, whereby movement of the anti-friction means to one side of the other of central position carries one of said transmitting members therewith, while the other is held relatively fixed, thereby stretching the resilient means so that the reactive force operates to return the anti-friction means to central position, and to maintain the same in assembled relation with said mounting when free from load.

Other and further objects of the invention will more fully and clearly appear from the description and claims hereinafter following.

In the drawing forming a part of this specification, Fig. 1 is a vertical, sectional view taken through the ends of the body and truck bolsters of a railway car, showing my invention in connection therewith. Fig. 2 is a top plan view of the antifriction bearing, showing my improvements in connection therewith. And Fig. 3 is a vertical sectional view through the anti-friction bearing detached from the truck bolster, and showing a slightly different embodiment of my invention.

Referring to Figs. 1 and 2 of the drawings, 10 indicates the underside of a body bolster, and 11 the upper side of the corresponding truck bolster of a railway car. My improved side bearing is shown as applied to the truck bolster and comprises

broadly, a housing or retainer A; anti-friction elements B—B; transmitting elements 55 C—C; and resilient means D—D.

The housing A is preferably of rectangular formation provided with curved end walls 13—13, vertically disposed side walls 14—14, and with a bottom 15, said bottom being provided with recesses 16 for the reception of the heads of rivets 17—17, which serve to secure the bearing plate 18 to the bottom wall 15 of the housing A. The housing A is provided at its lower end portions with 60 securing flanges 19—19 through which extend securing rivets 20—20 which secure the housing to the truck bolster. The side walls 14—14 extend beyond the lower portions of the curved end walls 13—13 to provide 70 strengthening webs 21—21.

Each of the side walls 14 of the housing A is provided with an elongated horizontally disposed slot 22 adjacent one end portion of said side wall, and adjacent the top edge 75 thereof, and is provided at the opposite end portion thereof with a similarly arranged elongated slot 23. Each of said side walls is also provided with a centrally disposed elongated slot 24 arranged adjacent the top 80 edge of the side wall in substantially the same plane as the slots 22 and 23.

Disposed in the housing A and adapted to move back and forth upon the bearing plate 18 are anti-friction means, which as 85 shown comprise two cylindrical rollers B—B.

The transmitting members C—C are two in number, one of the same being disposed outside of one of the anti-friction elements 90 B, and the other being disposed upon the opposite side of the other of the anti-friction elements B, each of said transmitting members C being in the form of an elongated cylindrical pin having its opposite ends projecting 95 outwardly through the slots 22 and 23 in the side walls, as indicated at 24, and the outer ends of the transmitting members C—C have connected therewith the resilient means D—D.

The resilient means D—D are two in number, one of the same being disposed on each side of the housing A and exteriorly of the side wall thereof, and each has its opposite ends connected to the adjacent ends of the 105 transmitting members C—C which project

said holes being sloped to induce a flow of oil in opposite directions.

What I claim is:

1. In a bearing, the combination of two relatively rotatable coaxial members, one of said members being provided with a lubricant reservoir or chamber, the wall of said last named member being pierced with holes communicating with said reservoir and with the bearing surface between said members, said holes being oppositely inclined respectively to radii to the axis of said members to induce a flow of lubricant to and from said reservoir.
- 15 2. In a bearing, the combination of two relatively rotatable coaxial members, one of said members being provided with a lubricant reservoir or chamber, the wall of said last named member being pierced with holes communicating with said reservoir and with the bearing surface between said members,
- 20

said holes being oppositely inclined respectively to radii to the axis of said members in planes perpendicular to said axis to induce a flow of lubricant to and from said reservoir.

3. In a bearing, the combination of two relatively rotatable coaxial members, one of said members being provided with a lubricant reservoir or chamber, the wall of said last named member being pierced with holes communicating with said reservoir and with the bearing surface between said members, said holes being oppositely inclined respectively to radii to the axis of said members, and spaced longitudinally of said axis to induce a flow of lubricant to and from said reservoir and longitudinally over said surface.

In testimony whereof I affix my signature.

STEPHEN I. FEKETE.

mitting element, will serve to return the element toward central position. A like action occurs upon movement of the anti-friction element B' in the opposite direction as will be understood.

While I have herein shown and described what I now consider the preferred manner of carrying out the invention, the same is merely illustrative, and I contemplate all changes and modifications that come within the scope of the claims appended hereto.

I claim:

1. In an anti-friction bearing, the combination with a housing provided with side and end walls, the side walls of said housing having horizontally arranged spaced slots therein; transmitting members extending transversely across said housing, and each having its opposite ends slidably mounted in the slots of said side walls; coiled springs connecting the opposite end portions of said transmitting members; and anti-friction means disposed in said housing and arranged between said transmitting members.

2. In an anti-friction bearing, the combination with a retainer; of anti-friction means mounted in said retainer and adapted to move back and forth with respect thereto; movable transmitting members arranged at opposite sides of said anti-friction means in the path thereof; means limiting inward movement of said transmitting members toward each other; and spring means connecting said transmitting members whereby movement of said anti-friction in one direction displaces one of said transmitting members to stretch said spring means, while the remaining member is held against movement, and movement of said anti-friction means in another direction displaces the other transmitting member to stretch said spring means in the same manner, said spring means operating in each instance to return the anti-friction means to central position.

3. In an anti-friction bearing of the character described, the combination with a retainer having side walls provided with spaced longitudinally extending slots; of anti-friction means adapted to move back and forth with reference to said retainer;

transmitting members extending transversely of said housing and having their opposite end portions slidably mounted in said slots; and tension springs arranged outwardly of the side walls of the said retainer and each having its opposite ends connected to the adjacent ends of said transmitting members.

4. In an anti-friction bearing of the character described, the combination with a housing having side walls each of which is provided with spaced horizontally disposed slots adjacent the opposite ends thereof, and a central slot arranged intermediate of said end slots; a plurality of anti-friction elements disposed in said housing and arranged to move back and forth with respect thereto; transmitting members disposed at the outer sides of said anti-friction elements in the path thereof, said transmitting members being slidably mounted in the slots in said side walls; a retainer member interposed between said anti-friction elements and slidably mounted in said central slots; and resilient means connecting said transmitting members for yieldably urging said anti-friction elements toward normal central position.

5. In an anti-friction bearing, the combination with a retainer; of a plurality of anti-friction elements adapted to move back and forth to either side of central position with respect to said retainer; transmitting members disposed at the outer sides of said anti-friction elements and engaging the same above the central axes thereof, said transmitting members being movable horizontally and restrained against vertical movement; resilient means normally urging said transmitting members into engagement with said anti-friction elements; and a retaining member interposed between said anti-friction elements and above the axial centers thereof and being mounted to have movement in the direction of movement of said anti-friction elements and restrained from vertical movement.

In witness that I claim the foregoing I have hereunto subscribed my name this 3rd day of February, 1926.

WILLIAM A. GEIGER.
